[57] **CLAIM**

The ornamental design for a storage cabinet, as shown and described.

DESCRIPTION

FIG. 1 is a perspective view of a storage cabinet showing my new design;

FIG. 2 is a left side elevational view, the right side being a mirror image thereof;

FIG. 3 is a front elevational view thereof;

FIG. 4 is a bottom plan view thereof;

FIG. 5 is a top plan view thereof;

FIG. 6 is a back elevational view thereof;

FIG. 7 is a side elevational view thereof, with the door in the open position;

FIG. 8 is a perspective view of a modified form of the storage cabinet shown in FIG. 1;

FIG. 9 is a left side elevational view the right side being a mirror image thereof;

FIG. 10 is a front elevational view thereof;

FIG. 11 is a bottom plan view thereof;

FIG. 12 is a top plan view thereof;

FIG. 13 is a back elevational view thereof; and,

FIG. 14 is a side elevational view thereof, with one of the doors in the open position.
